CLAIM

The ornamental design for an expandable electronic device accessory, as shown and described.

DESCRIPTION

FIG. 1 is a top plan view of a first embodiment of an expandable electronic device accessory showing our new design;

FIG. 2 is a bottom plan view thereof;

FIG. 3 is a bottom perspective view thereof, with the bottom surface of the accessory visible at the top of the figure;

FIG. 4 is a right side view thereof, which is a mirror image of a left side view thereof;

FIG. 5 is a front plan view thereof, which is a mirror image of a rear plan view thereof; and

FIG. 6 is a top perspective view thereof, with the top surface of the accessory visible at the top of the figure.

FIG. 7 is a top plan view of a second embodiment of an expandable electronic device accessory showing our new design;

FIG. 8 is a bottom plan view thereof;

FIG. 9 is a bottom perspective view thereof, with the bottom surface of the accessory visible at the top of the figure;

FIG. 10 is a right side view thereof, which is a mirror image of a left side view thereof;

FIG. 11 is a front plan view thereof, which is a mirror image of a rear plan view thereof; and,

FIG. 12 is a top perspective view thereof, with the top surface of the accessory visible at the top of the figure.

It is noted that any broken line illustration of environmental structure in the drawings is not part of the design sought to be patented.
